SOAP DISPENSER

James R. Findlay, 4861 Arvilla Drive S. 43623, and James C. Lower, 4729 Corey Road 43623, both of Toledo, Ohio

Filed July 24, 1972, Ser. No. 274,759

Term of patent 14 years

Int. Cl. D23—02

U.S. Cl. D6—95

FIG. I

FIG. 4

FIG. 2

FIG. 3

FIG. 1 is a perspective view of a soap dispenser embodying our new design;

FIG. 2 is a front view thereof;

FIG. 3 is a sectional view taken along line 3—3 of FIG. 2; and

FIG. 4 is a top view thereof.

We claim:

The ornamental design for a soap dispenser, substantially as shown and described.
